FRED SCHOENWOLF, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM WITH AUTOMATIC RINGING DISCONNECT.

1,273,189.

Specification of Letters Patent. Patented July 23, 1918.

Application filed November 27, 1914. Serial No. 874,163.

REISSUED

To all whom it may concern:

Be it known that I, FRED SCHOENWOLF, a citizen of the United States of America, resident of Chicago, county of Cook, and 5 State of Illinois, have invented certain new and useful Improvements in Telephone Systems with Automatic Ringing Disconnect, of which the following is a specification.

My invention relates to telephone systems 10 and has to do more particularly with automatic ringing systems such as are provided for operators' cord circuits, one of the principal objects of my invention being to provide an improved circuit arrangement

15 whereby the application of ringing current to the called line is interrupted and a disconnect signal given should the calling subscriber replace his receiver prior to receiving a response from the called substation.

20 In the accompanying drawing I have illustrated the preferred embodiment of my invention, the system shown including calling and called substations A and B respectively each terminating in line circuits

25 having the usual line relay LR, cut-off relay CO and line jacks. The line circuits shown are what are known as multiple lamp circuits in which a line lamp is provided for each jack so that when a call is initiated a line signal appears before each of the calling line jacks and any one of a plurality of operators may seize this call preferably to the exclusion of others.

The preferred form of cord circuit C is arranged 35 for interconnecting the telephone lines and includes an answering plug AP and calling plug CP connected by talking conductors indicated by heavily marked lines. In answering a call an operator in-

40 serts an answering plug AP into a line jack whereby the high resistance test relay T is energized to connect the answering supervisory relay AS in circuit with the cut-off relay CO so that relay AS is energized and

45 connects the operator's telephone O in circuit with the cord and thus with calling line. The answering tip relay AT also energizes to prevent the premature lighting of the answering supervisory lamp AL. In ex-

50 tending the call to the wanted line the operator inserts the calling plug CP whereby the calling sleeve relay CS energizes to again disconnect the operator's telephone

from the cord circuit. The operator then depresses the proper plunger of the ringing 55 key RK which connects the proper ringing generator by the common contacts of the key, causes an energization of a ringing control relay RC followed by the periodic energizations of an interrupter relay IR by a 60 circuit through the interrupter I. When the subscriber responds to the call a calling tip relay CT energizes interrupting the locking circuit for the ringing control relay RC to stop further application of ringing 65 current and efface the calling supervisory lamp CL.

Should the calling subscriber replace his receiver prior to the response of the called subscriber link disconnect relay LD energizes and in view of the fact that the locking circuit for the ringing control relay RC is controlled through contacts of relay LD, the ringing control relay deenergizes and prevents further application of ringing 75 current to the called line.

The energization of relay LD also interrupts the link or cord talking conductors and thereby restores the control of the line circuit to substation A so that the subscriber 80 thereat may immediately recall without awaiting the withdrawal of the answering plug AP. Although the preferred embodiment of my invention includes this instantaneous disconnect and recall it is to be understood 85 that my invention is not limited to circuits employing this method of operation.

Having described in general the different devices employed in the preferred embodiment of my invention and their functions, I will now describe more in detail the operation of the system shown.

A subscriber at substation A desiring to call, removes his receiver to establish a circuit for the corresponding line relay LR whereby the line signals before the different associated jacks are lighted. The first operator to seize the call by the insertion of an answering plug AP in one of the calling 95 line jacks, connects high resistance test relay T and cut-off relay CO in series effecting the energization of T. The closing of alternate contact 1 of relay T connects the comparatively low resistance answering 100 sleeve relay AS in series with cut-off relay 105

CO whereby relay AS energizes closing its alternate contact 2 to connect its winding directly to the sleeve strand of the cord independent of the contact of the test relay. 5 Therefore should relay T restore due to the shunting of its winding by the comparatively low resistance of AS, relay AS still remains energized through its locking contact 2. Due to the flow of current 10 through the windings of AS and T over the calling line and through the answering tip relay AT, said relay AT energizes to interrupt its normal contact 3 and prevent a premature lighting of the answering supervisory lamp AL and premature energization 15 of the link disconnect relay LD. Also responsive to energization of AS its alternate contacts 4, 5 are closed to connect the operator's telephone O in bridge of the talking conductors of the cord and thus to the calling telephone line.

Should a second operator insert a plug AP into another jack of the calling line subsequent to the insertion of the first plug, 25 the test relay T of this second cord does not energize due to the shunting of its winding by the relay AS of the first cord so that the second operator is unable to communicate with the calling subscriber because her 30 telephone set is not connected. Therefore this second operator again withdraws her answering plug AP.

The first operator having ascertained that connection is desired with substation B 35 tests a jack thereof in the usual manner and finding the line idle inserts the calling plug CP in a jack thereof. This act connects calling sleeve relay CS and cut-off relay CO¹ in series causing their energization, the 40 energization of CO¹ removing the substation control of its line signals and extending the connected jack and cord to the called line. The energization of CS by interrupting its normal contacts 9, 10, again disconnects 45 the operator's telephone from the cord. The operator now depresses the proper plunger by ringing key RK whereby the associated generator is connected to the ringing conductor 6. The actuation of the 50 ringing plunger to its fully depressed position also actuates the common contacts 7, 8 which are closed while the plunger is fully depressed but not when in its intermediate position. The closing of alternate 55 contact 8 establishes a circuit for ringing control relay RC traced from battery through the winding thereof, alternate contact 8, normal contacts 11, 12, and alternate contact 13, to ground. Relay RC therefore 60 energizes closing its alternate contact 14 to establish a direct locking circuit for its winding through normal contact 11, and 12 and alternate contact 13 to ground.

It will be noted that the locking circuit 65 for ringing control relay RC is traced

through normally closed contacts of relays LD and CT thereby placing the disconnection of ringing current under control of both the calling and called substations as will be described.

70 Relay RC having energized, interrupts its normal contacts 17, 18 to interrupt the talking strand and closes its alternate contact 19 to establish an operating circuit for interrupter relay IR through interrupter I. 75 Relay IR is therefore periodically energized to alternately connect ringing current and tip relay CT in circuit with the called line by action of its contacts 20, 21.

Upon response of the called subscriber 80 and the first following deenergization of IR, a circuit for tip relay CT is established traced from ground through the winding thereof, normal contact 20, alternate contact 22, over the line and returning through the 85 winding of CS to battery. The resulting energization of CT effects an interruption of its normal contact 12 which it will be remembered is included in the locking circuit of RC. Therefore relay RC deenergizes 90 opening its alternate contact 19 and maintaining the interrupter relay IR inert. The closing of the normal contacts 17, 18 establishes the continuity of the talking circuit 95 between the two substations.

Assuming now that the connection has been extended to the called line and that its substation was being rung, as before described, but that the calling subscriber replaces his receiver prior to receiving a response from the called substation. In such case the circuit for answering tip relay AT is interrupted causing its restoration whereby a circuit for link disconnect relay LD and supervisory lamps AL, CL is established. 100 The circuit for relay LD is established from battery through winding thereof, normal contact 3 and alternate contacts 26, 13 to ground. Relay LD therefore energizes to 105 interrupt the talking conductors of the link and thereby operatively disconnect the link from the calling line. Although this energization of LD interrupts the initial energizing circuit for AS and T by the opening of normal contacts 27, said relays AS and T 110 are maintained energized through alternate contact 27 to ground over contacts 26, 13. The ground connection from alternate contact 13 to normal contact 3, previously traced, is also effective to light supervisory 115 lamp AL and the closing of alternate contact 11 of relay LD lights calling supervisory lamp CL over a circuit traced from battery through CL, alternate contact 11, normal contact 12 to ground at alternate 120 contact 13. The operator having observed the two signals AL and CL lighted, withdraws plugs AP and CP from their respective jacks, the withdrawal of plug CP causing the restoration of relay CS whereby its 125 130

alternate contact 13 is interrupted. As relays LD, T and AS are held up over a circuit through this alternate contact 13, it will be seen that they are restored when said contact is interrupted.

It will be observed that when the subscriber A replaces his receiver prior to receiving a response from the called substation and relay LD energized to operatively dis-

10 connect the cord from the calling line, cut-off relay CO thereof restored so that the line of substation A was available for immediate recall. Therefore if the subscriber at substation A desires to initiate a recall without 15 awaiting the removal of plug AP from its jack, by again removing the receiver, line relay LR is energized to light the associated line signals so that the same or another operator may take the call.

20 When a connection has been effected between substations A and B in a manner as above described and both receivers are off their switch-hooks, establishing a conversational circuit, the replacing of these receivers 25 will light supervisory lamps AL and CL. Assuming the subscriber at B is the first to replace his receiver the circuit for relay CT is interrupted causing the closure of its normal contact 12 and establishing a circuit 30 for lamp CL from ground at alternate contact 13 of CS, normal contacts 12, 11, 14, 7 and lamp CL to battery. The replacing of the receiver at substation A causes the de-energization of AT followed by the energization 35 of LD and the lighting of lamp AL as already described. The operator will now withdraw the two plugs restoring the apparatus to normal.

It will be noted that relay LD is a slow 40 restoring type, this being to prevent the seizing of a recall by more than one link circuit. That is, assuming a connection is established between substations A and B and that after conversation the subscribers have 45 replaced their receivers to bring about the lighting of lamps AL and CL and the energization of LD. Should the calling subscriber at A initiate a recall prior to the removal of plug AP, the associated line signals will of course be lighted and should another operator than the one which controls 50 cord C seize this call, upon the withdrawal of plug CP of C the locking circuit for relays LD, T and AS is interrupted at alternate contact 13 of CS. Now if relays LD, T and AS were fast relays, and relay LD should restore prior to T and AS it will be seen that due to the closing of normal contact 55 27 of LD, relay AS would remain 60 locked up over the sleeve strand and therefore the operator of cord C would have her telephone connected to the calling line in multiple with the telephone of the other operator who has seized the recall. But due 65 to the slowness of relay LD, relays AS and

T will restore prior to LD, so that upon restoration of LD the associated relay T will not again energize and therefore its relay AS also remains inert and the operator at C is prevented from coming in on the seized 70 recall.

From the foregoing it will be seen that I have provided a system wherein secret service and instantaneous disconnect and recall are provided, together with automatic 75 ringing which when applied to a called line may be interrupted by a control exercised from either connected substation together with means for establishing the usual disconnect signal of two supervisory lamps. 80

In working out my invention I have applied it to a preferred form of cord or link circuit but I contemplate using it in connection with other circuits than that shown. It will also be apparent that changes and 85 modifications will readily occur to those skilled in the art after becoming familiar with my invention and therefore I do not desire to be limited to the exact structure as shown and described but aim to cover all 90 that which comes within the spirit and scope of the appended claims.

Having described my invention, what I claim as new and desire to secure by United States Letters Patent, is:

95 1. A telephone system comprising telephone lines, an operator's link circuit for interconnecting said lines, operator controlled means for applying ringing current and continuing such application to the called line, and means for interrupting such application of ringing current by a control exercised at both the calling and called substations.

100 2. A telephone system comprising telephone lines, an operator's link circuit for interconnecting said lines, answering and calling supervisory relays for said link circuit operable over the telephone lines, means for applying ringing current and continuing such application to the called line, operator controlled means for initiating the operation of said means, and means controlled by both supervisory relays for interrupting said application of ringing current. 110

115 3. A telephone system comprising telephone lines, an operator's link circuit for interconnecting said lines, a relay at each end of the link circuit operable over the telephone line connected at that end, means for applying ringing current and continuing such application to the called line, operator controlled means for initiating the operation of said means, and circuit connections including contacts of both of said relays 120 whereby said application of ringing current may be interrupted by a control exercised at both the calling and called substations.

125 4. A telephone system comprising telephone lines, an operator's link circuit for 130

- interconnecting said lines, means for applying ringing current and continuing such application to the called line, a pair of supervisory signals for the link circuit, and 5 means controlled over the calling line for interrupting such application of ringing current to the called line and lighting said supervisory signals for disconnection.
5. A telephone system comprising telephone lines, an operator's link circuit for interconnecting said lines, means for intermittently applying ringing current to the called line, operator controlled means for initiating the operation of said ringing 10 means, and means controlled by either the calling or the called subscriber for disconnecting the ringing current from the called subscriber's line.
6. A telephone system comprising a calling subscriber's and a called subscriber's line, an operator's link circuit for connecting said lines, operator controlled means for applying ringing current to the line of the called subscriber, and means controlled by 15 either of said subscribers for disconnecting said ringing current from said called subscriber's line.
7. A telephone system comprising telephone lines, an operator's link circuit for connecting said lines, means for intermittently applying ringing current to the called line, electromagnetic means controllable at the substation of the calling line for disassociating his line from the said link circuit, and means responsive to such disassociation 20 for interrupting the application of ringing current to the line of said called subscriber.
8. A telephone system comprising a calling and a called subscribers' line, a link circuit for connecting said lines, means included in said link circuit for automatically applying ringing current to the said called subscriber's line, electromagnetic means responsive to a control exercised at the substation of the calling line for disassociating said calling line and said link circuit, and means controlled by said electromagnetic means for interrupting the application of ringing current to the called subscriber's line.
- 50 9. A telephone system comprising telephone lines, an operator's link circuit for connecting said lines, means included in said link circuit for intermittently applying ringing current to the called line, a disconnect relay for disconnecting the calling subscriber's line from the link circuit, and means controlled by said disconnect relay for interrupting the application of ringing current to said called subscriber's line.
- 60 10. A telephone system comprising telephone lines, a link circuit for interconnecting said lines, means for intermittently applying ringing current to a called one of said lines, and means controlled at the substation of a calling one of said lines for dis- 65 associating his line from said link circuit and for interrupting such application of ringing current.
11. A telephone system comprising a pair of connected telephone lines, means for applying ringing current to one of said lines, means controlled at the substation of the other of said lines for disassociating said lines and for interrupting the application of ringing current to the first one of said lines. 70
12. A telephone system comprising a pair of connected telephone lines, means for applying ringing current to one of said lines, means controlled at the substation of one of said lines for disassociating said lines, and means controlled at the substation of either of said lines for interrupting such application of ringing current. 75
13. A telephone system comprising a pair of telephone lines, an operator's link circuit for connecting said lines, means included in said link circuit for applying ringing current to one of said connected lines, a disconnect relay controlled at the substation of the other of said lines for disassociating said last line and said link circuit, and means controlled by said disconnect relay for disconnecting the ringing current from the first one of said lines. 80
14. A telephone system including a calling and a called telephone line, an operator's link circuit for connecting said lines in conversational circuit, means for applying ringing current and continuing such application of the same to said called line, a pair of supervisory signals for said link circuit, and means controlled by the calling subscriber for interrupting such application of ringing current to the called line and for operating both of said supervisory signals. 85
15. A telephone system including a calling subscriber's line and a called subscriber's line, an operator's link circuit for connecting said lines in conversational circuit, a source of ringing current, means for intermittently applying said ringing current to the said called line, an operator's switch for initiating the operation of said intermittent means, and means controlled by the calling subscriber for causing the cessation of said intermittent means. 90
16. A telephone system including a calling subscriber's telephone line and a called subscriber's telephone line, an operator's link circuit for connecting said lines in conversational circuit, a source of ringing current, operator controlled means for applying said ringing current to the line of the called subscriber, and means controlled by the calling subscriber for disconnecting said source of ringing current from said called subscriber's line. 100
17. A telephone system including a calling and a called subscriber's line, an operator's 115

- link circuit connecting said lines in conversational circuit, a source of ringing current, means for intermittently applying said ringing current to the called subscriber's line, 45
- 5 operator controlled means for initiating the operation of said ringing means, and electromagnetic means controlled by the calling subscriber for preventing the intermittent application of ringing current to the called subscriber's line.
- 10 18. A telephone system including a calling subscriber's line and a called subscriber's line, an operator's link circuit provided with a pair of terminals for connecting said lines, 50
- 15 a source of ringing current, operator controlled means for connecting said ringing current to the said called subscriber's line, a relay controlled over the calling subscriber's line, and means controlled by said relay for 55
- 20 preventing a further application of ringing current to the said called subscriber's line.
19. A telephone system including a calling subscriber's line and a called subscriber's line, an operator's cord circuit for connecting 60
- 25 said lines, a source of ringing current, means for intermittently applying said ringing current to the called subscriber's line, operator controlled means for initiating the operation of said applying means, and means controlled 65
- 30 by the replacement of the receiver at the calling substation for preventing said applying means from further connecting ringing current to the called subscriber's line.
20. A telephone system including a calling subscriber's line and a called subscriber's line, an operator's cord circuit for connecting said lines, a source of ringing current, means for intermittently applying said ringing current to the called subscriber's line, operator 70
- 35 controlled means for initiating the operation of said applying means, an answering supervisory signal, and a relay controlled by the calling subscriber when he signals for dis- 75
- 40 connection for operating said supervisory signal and for preventing the further application of said ringing current to said called subscriber's line.
21. A telephone system including a calling subscriber's telephone line and a called subscriber's telephone line, means provided with manual terminals for connecting said lines, ringing mechanism including a relay adapted to be energized intermittently to apply ringing current to the called subscriber's line, means controlled by a central office operator 50
- 45 for associating said mechanism with the said called subscriber's line, and automatic means controlled by the calling subscriber for disassociating said ringing mechanism from the said called subscriber's line thereby preventing further intermittent applications of ringing current to the called subscriber's line.
22. A telephone system including a calling subscriber's telephone line and a called subscriber's telephone line, an operator's link circuit for use in connecting said lines, a source of ringing current, a relay adapted to be operated intermittently to connect said ringing current to said called subscriber's line, a ringing control relay controlling the operation of said first relay, means for operating said ringing control relay to initiate the operation of said first relay, and electromagnetic means controlled by the calling subscriber for deenergizing said ringing control 60
- 50 relay to prevent further operation of said first relay, thereby preventing further intermittent applications of ringing current to the said called subscriber's line.

Signed by me at Chicago, county of Cook, 80
and State of Illinois, in the presence of two
witnesses.
